UNITED STATES PATENT OFFICE.

JOHN B. HIPWELL, OF READING, PENNSYLVANIA, ASSIGNOR TO WINDSOR MACHINE CO., OF READING, PENNSYLVANIA, A CORPORATION.

MACHINE FOR SEWING LOOPED FABRICS.

No. 853,015.

Specification of Letters Patent.

Patented May 7, 1907.

Application filed October 16, 1905. Serial No. 282,921.

To all whom it may concern:

Be it known that I, JOHN B. HIPWELL, a citizen of the United States, residing in the city of Reading, county of Berks, and State 5 of Pennsylvania, have invented certain new and useful Improvements in Machines for Sewing Looped Fabrics, of which the following is a specification.

My invention relates to machines such as 10 are commonly employed for stitching together the edges of looped fabrics, and it consists in an improved slackening mechanism for the uniting stitches as particularly described in connection with the accompanying 15 drawing illustrating a preferred application of the same to a well known form of looping machine; the novel features being specifically pointed out in the claims.

Figure 1 is a partly sectional elevation of 20 a looping machine having my invention applied thereto. Fig. 2 is a partial plan view of the same. Fig. 3 is an enlarged diagrammatic view indicating the operation of my improved slackening attachment.

25 Referring briefly to the well known features of the looping machine indicated, the edges of the looped fabrics 22 which are to be united, are engaged upon the horizontally arranged circular series of projecting pins 3 30 on the ring 4, to which latter intermittent rotary movements are imparted, each equal to the spacing-apart of the successive fabric-engaging pins. In connection with this fabric-carrying means, a vibrating needle 5 35 and hooked looper 6 are so operated that said needle vibrates over each pin, as they are successively moved into its line of travel, and through the projecting loops of the fabrics; while the looper delivers a previously formed loop and takes up a new loop 40 from the needle thread; in such manner as to form a chain of stitches uniting the edges of the fabric.

In order to secure required elasticity in 45 the uniting seam it is necessary that this chain of stitches be so loosely drawn as to provide approximately the same yield as in the fabric itself; and my invention provides for securing this result in an improved manner as hereafter described with reference to the particular mechanism shown in the drawing.

In the ordinary looping operation, as already briefly stated, the looper 6 delivers a

thread-loop previously formed upon it, at 55 each pass of the reciprocating needle; this being effected, as is well known in the art, by a slight transverse movement of the looper after the needle in such pass has passed through said thread-loop so as to strip it off 60 the moving looper; and a new loop of the needle-thread being formed thereon by the return movement of the looper. In my improved slackening attachment this stripped-off thread-loop instead of remaining upon the 65 retracting needle is delivered to a reciprocating slackening-finger 10, which is moved laterally into each loop while it is still retained upon the looper. Owing to the fact that the opening of the loop is very narrow where it 70 joins the fabric upon the butts of the pins 3, it is necessary to pass the finger through the loop at a point some distance away from the fabric and adjacent the looper where the width of the loop opening is sufficient to insure 75 the passage of the finger through the loop. To enable this single device (the finger 10) thus introduced to the loop at some distance from its base, to serve directly as a means of preventing undue tightening of the stitch, I 80 provide for temporarily holding the loop upon it, after the latter is delivered by the looper, during the tightening movement of the needle, so that when released by the withdrawal of the finger, it will be loosely 85 drawn as desired. As shown, this slackening-finger 10 is adjustably clamped to a carrier arm 11 pivoted at 12 to a fixed support 13, and arranged to be swung to and fro by the action of a spring 14 and a cam 15 on a shaft 90 16 of the machine, so as to reciprocate the finger 10 transversely across the fabric-engaging pins 3 at proper times and with the proper interval of rest to receive hold, and release the thread-loop as above stated. This action of 95 the finger 10 in effecting the loosening of the chain of uniting stitches will be readily understood by reference to Fig. 3, in which the thread-loop 20 which was previously formed upon the looper 6 and stripped therefrom by 100 a lateral movement of the latter, is represented as held upon the slacker-finger 10 while a new loop is formed upon the returned looper. It will be seen that the further retraction of the needle 5 will merely draw the 105 loop 20 tight upon the finger 10 until the latter is moved laterally out of engagement therewith by the action of the cam 15, after

which the movement of the needle will draw up the stitch loosely as desired, so as to secure the required elasticity at the united edges of the fabric while the finger 10 is 5 quickly returned through the succeeding loop formed upon the looper.

Provision is made, as shown, for regulating the distance from the fabric at which the finger 10 engages the loop, and for timing its 10 movement, as is required for varying the looseness of the stitch, by forming the carrier arm 11 with an adjustably fixed finger-engaging end to which the finger is adjustably secured by suitable clamping screws as indicated; and by adjustably securing the cam 15 to the shaft 16, and the contacting projection 21 on the carrier arm, so that both the position of the finger in the loop and the timing and extent of its movement may be readily and accurately regulated.

The particular application of my invention which has been thus specifically described may obviously be modified without materially departing therefrom.

25 What I claim is:—

1. In a looping machine the combination with the fabric-carrying pins and stitch-forming mechanism comprising a reciprocating needle and a looper, of a reciprocating 30 slackening finger and operating means whereby said finger is caused to move laterally into

each successively formed loop at a point remote from the fabric, to receive the loop directly from the looper and to limit the closing 35 of the same by the tightening movement of the needle to a determined length from the fabric until withdrawn therefrom by the reverse finger movement, said finger constituting the sole holding means for the loop during the tightening thereof substantially as 40 set forth.

2. In a looping machine the combination with the fabric-carrying pins and stitch-forming mechanism comprising a reciprocating needle and a looper, of an adjustable reciprocating finger and adjustable operating 45 means whereby said finger is caused to move laterally into each successively formed loop at a regulated distance from the butts of said pins, to receive the loop directly from the 50 looper, and to hold the same for a regulated time during the tightening movement of the needle, said finger constituting the sole holding means for the loop during the tightening thereof substantially as 55 set forth.

In testimony whereof, I affix my signature, in the presence of two witnesses.

JOHN B. HIPWELL.
